UNITED STATES PATENT OFFICE.

WARREN CHARLES DRAKE, OF INWOOD, NEW YORK.

FURNACE.

1,400,036.

Specification of Letters Patent. Patented Dec. 13, 1921.

Application filed October 13, 1919. Serial No. 330,428.

To all whom it may concern:

Be it known that I, WARREN CHARLES DRAKE, a citizen of the United States, and a resident of Inwood, in the State of New York, 5 have invented certain new and useful Improvements in Furnaces, of which the following is a specification.

My invention relates to furnaces having admission of air into the fuel bed through 10 the side walls of the furnace, and particularly to furnaces in which such side walls are made of fire-brick. It has been found that in fire brick constructions considerable trouble arises from the formation of clinkers on the side walls of the furnace and on 15 the bridge-wall which confines the fuel bed on one side, and such clinkers sometimes adhere to the walls and obstruct the operation of the furnace. Thorough combustion is also 20 impeded by such clinkers. The forcible removal of these clinkers from the walls, which has been resorted hitherto generally, is not only a tedious procedure, but liable to injure the fire-brick. For the purpose of over- 25 coming these difficulties, it has been known, for example in my prior application Number 242,585, filed June 29, 1918, and in Bernitz Patent Number 1,393,606 granted October 11, 1921, to use a fire-brick construction in 30 which the fuel bed is confined at the sides between brick walls spaced from the respective outer furnace walls to form a space into which air is introduced under pressure and from which such air passes into the fuel bed 35 through passages formed in said fire-brick structure. The present invention, relating to such clinker preventing refractory furnace walls involves certain important features of improvement, including the fol- 40 lowing: I supply a forced draft of air, steam or other fluid into the side of the fuel bed through apertures, which are tapered so as to give forcible tapering jets, which carry further into the fuel bed, giving a more ef- 45 fective clinker preventing action and protection of walls, while at the same time bet- 50 ter promoting combustion. The furnace wall face adjacent to the fuel bed is formed with channels or gutters into which the 55 apertures discharge; these channels serving to protect the apertures from clogging by the fuel or clinkers and permitting better lateral distribution of the entering air. These features and the combination of them 55 have proved very effective and successful in

practice. Other features will be explained in the further description of the invention.

Without desiring to restrict myself to the specific structure shown, I will now describe preferred and satisfactory embodiments of my invention, as shown in the accompanying drawings, it being understood that various modifications may be made without departing from the principles of my invention as set forth in the appended 60 claims.

In said drawings Figure 1 is a vertical section taken roughly on line 1—1 of Fig. 2 showing a furnace of the inclined under-feed stoker type, the walls of the combustion chamber having fire-bricks embodying my present invention, the parts exterior to the furnace and the retorts and twyters within the furnace being shown in elevation; Fig. 2 is a horizontal section on line 2—2 of Fig. 1; Fig. 3 is an enlarged detail view of one of the fire-bricks shown in Figs. 1 and 2; Figs. 4 and 5 are cross sections on lines 4—4 and 5—5 respectively of Fig. 3; Fig. 6 is a face view of another form of fire-brick 70 according to my invention; Fig. 7 is a section on line 7—7 of Fig. 6; Fig. 8 is a face view of a third form of fire-brick constructed in accordance with my invention; and Fig. 9 is a side view of the brick shown 75 in Fig. 8. The three face views, Figs. 3, 6 and 8, show the inner faces of the bricks, that is to say, those next to the combustion chamber.

The fuel introduced into the hopper 1 is 80 fed into the retort 2 by means of rams 3 re- reciprocating in ram boxes 4, this motion being obtained by means of connecting rods 5, a crank shaft 6, worm gearing 7, and a shaft 8, driven in any suitable manner.

The fuel thus fed into the furnace is 85 spread on twyters 9 to form a fuel bed the upper outline of which is indicated by the dotted line 10 in Fig. 1. Air to support combustion is supplied to the furnace from 100 a main air duct 11 and connecting duct 12. At 13 I have indicated an overfeed grate section and at 14 the dumping grate for the removal of clinkers and ashes. The furnace also has a combustion chamber bounded at 105 its four sides by the front wall 15, side walls 16, and a bridge wall 17. Some of the boiler tubes are indicated at 18. The parts numbered from 1 to 18 inclusive may be of any well-known or approved construction, ex- 110 cept in so far as the walls 15, 16, 17 are modi-

fied to receive the special fire-bricks to be described presently.

It will be seen from Fig. 1 that the vertical surfaces of the combustion chamber are given a special construction where they are in contact with the fuel bed. At these portions, the walls 15, 16 and 17 are recessed or chambered to receive fire-bricks of the novel type forming the subject-matter of the present application.

In the specific embodiment illustrated by Figs. 1 to 5, each of the fire-bricks 19 is made with air passages 20, two in an upper row, two in a lower row, and one in the center, at the point of intersection of the diagonals of the square or rectangle at the corners of which the other four passages are placed. The inner or discharge portions of the passages 20 do not extend to the inner face 19' of the brick 19, but terminates short of said face, being connected with intercommunicating surface channels or recesses 20', in the nature of shallow grooves or gutters, interrupting the otherwise generally flush interior surface of the walls, and shown extending up and down and also across the face of the brick. Preferably the passages 20 taper gradually from their inlets to their discharge ends, to deliver more forcible or concentrated jets of air. This important feature operates by deepening the zone of penetration, thereby keeping the hottest flames farther from the wall, to its protection, also holding off from the wall the possible area of clinker formation; so that any clinkers formed are not able to contact and fuse with the wall as occasionally occurred with the prior structures mentioned. The fire-bricks 19 are placed in the chambered portions of the walls 15, 16, 17 in such a manner that the faces 19' of said bricks are flush with the combustion chamber surfaces of said walls. The bricks 19 are in contact not only with said walls, but with each other, and may therefore be bonded properly, thus obtaining a very strong construction. At their outer surfaces, the bricks 19 are made with lugs or projections 21, located at the four corners, and serving to space the rear or outer faces 19'' of the bricks from the adjacent face of the wall 15, 16, or 17, so that an air-chamber 22 will be formed adjacent to each brick 19. All the air-chambers 22 along the same wall 15, 16 or 17 are in communication with each other. Air is supplied to the chambers 22 through suitable conduits, as indicated at 23'' in Fig. 1 and 2, and Fig. 1 also indicates a damper or valve to regulate the supply of air, it being understood that the air is preferably supplied under pressure, say from the main air duct 11, see Fig. 1.

In Figs. 6 and 7, the brick or block 19^a has its faces 19' and 19'', five tapering passages 20, and four corner lugs 21' disposed

in practically the same fashion as in Figs. 1 to 5, but the channels or recesses 20" cross each other in the shape of an X, instead of being horizontal and vertical as are the channels 20'.

Both in the form Figs. 1 to 5 and in the form Figs. 6 and 7, the surface channels 20' or 20" respectively at the discharge ends of the passages 20 communicate with each other. This however is not essential, and in Figs. 8 and 9, I have illustrated a brick 19^b having three separate or disconnected vertical surface channels or recesses 20^a, the middle channel communicating only with the central passage 20, while each of the lateral channels 20^a, communicates with two of the said passages 20, there being five such passages, placed as described above. It will be obvious that the number and arrangement of passages may be varied, and while I have shown each passage as formed within a single brick, I do not wish to restrict myself to this feature, since (preferably tapering) passages might be formed in other ways to extend through the fire-brick wall or structure and to terminate in recesses or channels on the inner face of such structure. Figs. 8 and 9 also show spacing lugs 21'' placed midway between the ends of the bricks instead of at the corners, as in the case of the lugs 21 or 21'.

The admission of air through the passages 20 prevents in a large measure the formation of clinkers which might adhere to the fire-bricks, particularly in view of the strong blasts or jets delivered through the passages when they are tapered as described. If however clinkers should form and run down the inner faces 19' of the fire-bricks, such clinkers will be kept away from the discharge ends of the passages 20, since these discharge ends are spaced from said inner faces, owing to said passages terminating at recesses such as 20', 20'', and 20^a, especially as these recesses are narrow. These channels or recesses also have a beneficial effect in spreading the air issuing from the passages 20, over a comparatively large area of the fuel bed.

While in Fig. 1 fire-bricks of the improved type are shown only at that part of the combustion chamber which is in contact with the fuel bed, I desire it to be understood that such fire-bricks may be applied above the line of the fuel bed, if desired, and this may be preferred in some cases to insure a more nearly perfect combustion.

The features shown herein and also shown in my said prior application are not herein claimed, but are reserved, for claim in the prior application; but what I do claim herein are the features not shown in the prior application, namely:

1. In a furnace a refractory wall bounding the combustion chamber, the same formed

with face channels or gutters facing the fuel bed within the chamber and with numerous tapered apertures each arranged with its outlet in the bottom of one of said face channels so as to conduct jets into said channels, and means for supplying air or other fluid under pressure to said apertures.

2. In a furnace a refractory wall bounding the combustion chamber, the same having its interior face adjacent the fuel bed built up of fire blocks each having its face formed with channels or gutters facing the fuel bed, and having apertures discharging into said channels, and means for supplying air or other fluid under pressure to said apertures.

3. A refractory fire brick or block for furnace walls, the same having face channels or gutters at its inner face and tapered air passages arranged with their outlets in such channels.

4. A refractory fire brick or block for furnace walls, the same having a plurality of short disconnected face channels or gutters

at its inner face and tapered air passages 25 arranged with their outlets in such channels.

5. A structure as in claim 2 and wherein the face channels of said wall are numerous short disconnected shallow channels or gutters, each having one or more of said apertures opening thereinto, and serving to keep 30 the apertures free from clogging.

6. In a progressive-feed forced-draft furnace, a non-clinkering refractory wall bounding the combustion chamber, the same having its inner portion adjacent the fuel bed built up of refractory blocks, formed with numerous tapered apertures, giving tapering jets of air, and mainly located to deliver such tapering jets directly into the fuel bed, and 40 means for supplying air under forced draft to such tapered apertures, whereby air of combustion so penetrates the fuel bed adjacent the wall as substantially to prevent clinker formation within attaching proximity 45 to the wall.

WARREN CHARLES DRAKE.
